METHOD OF MAKING SQUARE-HEAD SCREWS

Harrington Moore, Medford, Mass.

Application May 7, 1934, Serial No. 724,367

2 Claims. (Cl. 10—10)

This invention relates to an improved method of making screws having square heads or heads of other polygonal shapes, the method being more especially adapted to be practiced with automatic machinery for carrying out the several steps in the making of screws.

It is an object of the invention to make square-head screws without heating the stock, and to make them in such a manner that they will be substantially free from internal weakness and from excessive variation in the shape and dimensions of the head.

For a more complete understanding of the invention, reference may be had to the description thereof which follows, and to the drawing of which

Figure 1 is a perspective view of a typical square-head screw made according to the invention.

Figure 2 is a fragmentary elevation of wire stock from which the finished screws are made.

Figure 3 is an elevation, partly broken away to show in section, of a screw at an intermediate stage of its production.

Figure 4 is a fragmentary sectional view of mechanism for swaging the head of a screw.

Figure 5 is a section on the line 5—5 of Figure 4.

Figure 6 is a fragmentary section similar to Figure 4, showing the parts in a different position of operation.

Figure 7 is a section on the line 7—7 of Figure 6.

In practicing the improved method of making screws, wire stock of suitable diameter is preferably employed, a piece of such stock being illustrated at 10 in Figure 2. The stock may be cut as at 11 to provide a blank 12 of predetermined length just sufficient for the finished screw. An end portion of the blank 12 is then swaged by suitable mechanism well known in the art to form a mushroom head 13 having a top face 14 which is flat or nearly so, and a rounded shoulder 15. This mushroom head is formed preferably prior to the formation of any screw thread on the shank of the blank. The head 13 is of substantially greater diameter than the shank, so that the headed blanks can readily be fed into an automatic thread-cutting machine. In swaging the end portion of the blank 12 to form the head 13, the volume of the head is carefully predetermined so as to be just sufficient to form the head of the finished screw.

After the formation of the mushroom head 13 on the blank 12, a screw thread 16 is cut or

otherwise formed on the shank of the blank 12. The blank is then ready for the final step of pressing the mushroom head laterally at spaced points so as to swage the head into a shape having an approximately polygonal cross section, preferably square. This operation is preferably performed while the blank is cold. To this end, the blank may be inserted in a suitable hole 17 in a holder 18. Associated with the holder 18 are pressing members 20, the hole 17 being of such a depth that the mushroom head 13 is in correct position for engagement by the pressing elements 20. In the apparatus illustrated on the drawing, four pressing elements 20 are illustrated for the formation of a square-headed screw, but it is evident that any desired number from two up can be employed to form heads having a plurality of flat side faces. In order to hold the blank in place in the hole 17 during the pressing operation, a spring-pressed plunger (not shown) preferably bears on the top face 14 of the mushroom head, this plunger being adapted to yield readily, so that, when the head is swaged, the axial flow of the metal is not impeded by the yielding plunger. When the blank 25 is properly in position as illustrated in Figures 4 and 5, the pressing elements 20 are forced to the position illustrated in Figures 6 and 7, these pressing elements engaging the mushroom head 13 laterally at spaced points. The pressing elements 20 form flat faces on the sides of the head and swage the head into the approximate square shape illustrated at 22 in Figures 6 and 7.

The size and shape of the mushroom head are preferably such that, when the sides are pressed 35 to form the finished head with predetermined transverse dimensions, there will be left a portion of the rounded shoulder 15 at 23. Thus sharp edges and corners on the head are avoided, 40 and the screw is given a finished appearance.

As it is evident from Figures 4 and 6, the diagonal dimension of the squared head 22 is approximately equal to the diameter of the mushroom head 13. The cross-sectional area of the squared head 22 is obviously less than that of the mushroom head 13. Hence, since the volume of the head is unchanged by the swaging operation, the axial length of the squared head must be greater than that of the mushroom head. 50 This increased axial length of the head results from an axial flow of the metal as the mushroom head is laterally pressed. This operation is such as to create no internal faults in the screw, the head of the screw thus formed being 55

fully as strong as those of screws made by previously known and practiced methods.

I claim:

- 5 1. A method of making a screw, which comprises swaging an end portion of a piece of wire stock of predetermined length to form a mushroom head having a predetermined volume just sufficient for the head of the finished screw, forming a screw thread on the shank of said piece, and thereafter cold-pressing the sides of said mushroom head simultaneously at a plurality of spaced points to swage the head into a polygonal shape having an increased axial length and a minimum cross-sectional dimension substantially equal to the dimension of the shank.
- 10 2. A method of making square-headed screws,

which comprises swaging an end portion of a piece of wire stock of suitable length to form a mushroom head of predetermined volume just sufficient for the head of the squared head to be formed, screw-threading the shank of said piece of stock, thereafter supporting the threaded piece so as to be capable of yielding axially, and cold-pressing the head of the piece laterally at four spaced points to form a squared head having a diagonal substantially equal to the diameter of the mushroom head before the pressing operation and a minimum diametrical dimension substantially equal to the diameter of the shank.
